UNITED STATES PATENT OFFICE.

HENRY G. ROTH, OF MINNEAPOLIS, MINNESOTA.

DISPLAY-FIXTURE.

SPECIFICATION forming part of Letters Patent No. 678,688, dated July 16, 1901.

Application filed January 24, 1901. Serial No. 44,552. (No model.)

To all whom it may concern:

Be it known that I, HENRY G. ROTH, a citizen of the United States, residing at Minneapolis, in the county of Hennepin and State 5 of Minnesota, have invented certain new and useful Improvements in Display-Fixtures; and I do hereby declare the following to be a full, clear, and exact description of the invention, such as will enable others skilled in the 10 art to which it appertains to make and use the same.

My present invention relates to wall display-fixtures especially adapted for use in retail stores to give to the walls an artistic appearance and to afford a support for various 15 advertisements; and to these ends the invention consists of the novel devices and combinations of devices hereinafter described, and defined in the claims.

20 The invention is illustrated in the accompanying drawings, wherein like characters indicate like parts throughout the several views.

Figure 1 is a side elevation of a knockdown 25 fixture constructed in accordance with my invention, the sections of the same being shown as laid out flat or as nearly flat as possible. Fig. 2 shows the same sections folded closely, as for shipment. Fig. 3 shows the fixture as 30 set up and secured in working position in the angle between the wall and the ceiling. Figs. 4, 5, 6, and 7 are diagrammatic views showing various designs which may be formed by the fixture-sections above indicated. Fig. 8 35 is a view corresponding to Fig. 2, but showing much thinner plates connected by flexible hinge-joints. Fig. 9 illustrates a modified form of the fixture, the same being shown in side elevation. Fig. 10 is a similar view 40 of the fixture shown in Fig. 9, but showing the same as folded. Fig. 11 is a detail in plan, showing the form of hinge used to connect the plates. Fig. 12 is a section on the line $x^{12} x^{12}$ of Fig. 11; and Fig. 13 is a plan 45 view of the lower section of the fixture illustrated in Fig. 9, some parts being broken away.

In the fixture here illustrated the sections 50 are connected by hinge-joints, and each section comprises several curved plates, which are bent on such lines that they are adapted to closely fit when folded.

The fixture illustrated in Fig. 3 is made up of three curved plates a and two flat plates a' and a^2 , which plates are connected at their 55 edges by hinged joints a^3 . In the construction illustrated in Fig. 8 these hinge-joints are assumed to be formed by strips of canvas or other flexible material, while in Figs. 1, 2, and 3 ordinary metallic hinge-joints are 60 employed. In the said views, however, the metal material from which the plates are formed is shown as much thicker than would actually be employed, and the hinge-joints are consequently shown as larger than would be 65 required. In practice the plates would fold much more closely than shown in Fig. 2, and with the canvas or flexible hinges shown in Fig. 8 the curved plates would fold close together. The part a^2 , which is in the nature 70 of a brace, need not be in the form of a plate, but may be in the form of a bar or rod. At its free end it is provided with a hook a^4 , which coöperates with a detent a^5 , secured on the concave surface of the nearest of the 75 three curved plates a . When the fixture is formed as shown in Fig. 3, it may be detachably secured to the wall by nails b , and the hook a^4 of the brace a^2 by engagement with the detent a^5 holds the intermediate portion 80 of the exposed section of the fixture against outwardly or inwardly bulging movements.

The connected series of plates indicated in Figs. 1 to 3 may be used in a great many different ways to form fixtures of various 85 designs. Several of these designs are indicated in Figs. 4 to 7, inclusive, wherein the manner of securing the same by means of the nails b is made obvious. Of course instead of nails other devices, such as screws or hooks, may 90 be employed.

In the construction illustrated in Figs. 9 to 13, inclusive, the curved plates f are connected by hinge-joint f' , afforded by strips of canvas secured to the adjacent edges of said 95 plates. These plates f have the same curve, so that they are adapted to be folded together, as shown in Fig. 10. The lower plate f is formed as a part of a box-like section f^2 , the top of which is left open, as shown in Fig. 13. 100 One or more nails or similar devices b , driven through the back of the box f^2 , serve to detachably support the fixture in position on the wall.

The upper curved plate f has rigidly formed or secured angular sides or end plates f^3 , to which supplemental leaves or side plates f^4 are connected by the same kind of hinge-joints f' . (Indicated in Figs. 11 and 12.)

When the fixture is placed in working position, as indicated in Fig. 9, the ends of the box f^2 , together with the plates f^3 and f^4 , lie flush and inclose the ends of the fixture-section. When the fixture is folded up, as indicated in Fig. 10, the leaves of folding plates f^4 are folded against the back of the upper section formed by the plates f and f^3 , and the folded fixture then has a rectangular box-like form.

It will of course be understood that modifications other than those above indicated may be made within the scope of my invention. It will also be understood that the so-called "plates" may be formed of various materials, such as metal, cardboard, or wire-woven screen.

What I claim, and desire to secure by Letters Patent of the United States, is as follows:

25 1. A knockdown wall display-fixture, com-

prising a plurality of curved plates connected by hinges at their adjacent edges, and adapted to be closely folded, substantially as described.

2. A knockdown wall display-fixture comprising a plurality of plates connected by hinges at their adjoining edges, and adapted to be secured in different relative positions, to produce various configurations.

3. A knockdown wall display-fixture having curved display plates or sections of approximately the same curves, adapted to closely fit when the fixture is knocked down, substantially as described.

4. A knockdown wall display-fixture, having curved display plates or sections adapted to closely fit when folded, which plates or sections are connected by hinges at their adjoining edges, substantially as described.

In testimony whereof I affix my signature 45 in presence of two witnesses.

HENRY G. ROTH.

Witnesses:

MABEL M. MCGRORY,
F. D. MERCHANT.
